UNITED STATES PATENT OFFICE

KURT H. ROY AND ROSS R. SWEANEY, OF LOS ANGELES, CALIFORNIA

DESIGN FOR A BOOK END

Application filed June 28, 1932. Serial No. 44,213. Term of patent 3½ years.

To all whom it may concern:

Be it known that we, KURT H. ROY and Ross R. SWEANEY, citizens of the United States, residing in Los Angeles, in the county of Los Angeles and State of California, have invented a new, original, and ornamental Design for Book Ends, of which the following is a specification, reference being had to the accompanying drawing, forming a part thereof.

In the accompanying drawing:

Fig. 1 is a front view of a book end showing our new design.

Fig. 2 is an end view.

Fig. 3 is a top plan view.

We claim:

The ornamental design for a book end as shown.

KURT H. ROY.
ROSS R. SWEANEY.
